UNITED STATES PATENT OFFICE

122,039

DESIGN FOR A GAUGE GLASS CLEANER

William H. Van Gaasbeek, East Orange, N. J.

Application February 17, 1940, Serial No. 90,334

Term of patent 7 years

To all whom it may concern:

Be it known that I, William H. Van Gaasbeek, a citizen of the United States, residing at East Orange, county of Essex, State of New Jersey, have invented a new, original, and ornamental Design for a Gauge Glass Cleaner, of which the following is a specification, reference being had to the accompanying drawing, forming part thereof.

In the accompanying drawing—

Fig. 1 is a side elevational view of a gauge

glass cleaner showing my new design; and

Fig. 2 is a top plan view thereof.

The present design comprises a gauge glass cleaner characterized by a cylindrical body having a constriction in which is confined a spiked collar, the spikes thereof having a propeller-like twist substantially as shown.

I claim:

The ornamental design for a gauge glass cleaner, substantially as shown and described.

WILLIAM H. VAN GAASBEEK.
